UNITED STATES PATENT OFFICE.

KARL RUDOLF ESSIG, OF LEIPSIC, ASSIGNOR TO THE FABRIK LOCHMANN-SCHER MUSIKWERKE ACTIEN-GESELLSCHAFT, OF LEIPSIC-GOHLIS, GERMANY.

STRIKER OR PICKER FOR GUITARS.

SPECIFICATION forming part of Letters Patent No. 555,599, dated March 3, 1896.

Application filed June 11, 1895. Serial No. 552,468. (No model.)

To all whom it may concern:

Be it known that I, KARL RUDOLF ESSIG, of Leipsic, in the Kingdom of Saxony and German Empire, have invented a new and useful Improved Striker or Plectrum for Zithers and the Like Stringed Musical Instruments, of which the following is a specification, reference being had therein to the accompanying drawings.

10 This invention has for its object a striker or plectrum for stringed instruments which admits of a soft and elastic plucking or striking of the strings and which may also be passed over the strings, so that an irregular plucking or sounding is entirely prevented.

15 The invention is shown on the accompanying drawings, in which—

Figure 1 is a side elevation from the right-hand side; Fig. 2, a rear elevation, and Fig. 3, 20 a side elevation from the left-hand side.

The constructive arrangement of this improved plectrum or striker is explained as follows:

25 The holder or handle *a* of the plectrum is provided at its end with a hook-like projection having a curved sliding surface standing at an acute angle to its longitudinal axis. This latter surface is provided with a covering *c*, of leather or felt, which latter also covers a piece 30 of the back of the plectrum-holder. On the rear of the plectrum-holder the plucking or striking-plate or plectrum proper, *b*, which is formed of horn, wood, vulcanite, or the like, is fastened by means of a screw *e*, an india-

rubber disk *d* being inserted, however, between the screw and the plate.

By the elastic layer *c* beneath the plectrum *b* and the arrangement of a washer *d* of soft india-rubber an even and elastic plucking of the strings is rendered possible both for the 40 softest "piano" as well as in the loudest "forte" playing, so that soft, full, ringing tones are obtained.

The evenness of striking is obtained by means of the sliding surface of the hook-shaped end of the plectrum or striker and the covering *c* thereon.

What I claim, and desire to secure by Letters Patent of the United States, is—

An improved striker or plectrum for zithers and the like stringed musical instruments, having a hook-shaped projection, the curved sliding surface of which is provided with a covering of leather, felt, or the like, while the rear of the striker bears an adjustable plucking-plate or plectrum of horn, wood or vulcanite, which is elastically held between two layers of leather, felt or india-rubber, with the object of rendering possible an even and elastic plucking of the strings substantially as 55 described and illustrated.

In testimony whereof I have signed my name to this specification in the presence of two subscribing witnesses.

KARL RUDOLF ESSIG.
